ATTORNEY

UNITED STATES PATENT OFFICE.

EDMUND CLIFTON CARVER, OF BURGESS HILL, ENGLAND.

APPARATUS FOR SUPPORTING AND STRAINING LAWN-TENNIS AND LIKE NETS.

Application filed November 10, 1927, Serial No. 232,416, and in Great Britain December 10, 1926.

This invention relates to the posts or supports and apparatus used for supporting or straining nets used in playing the game of lawn tennis or the like.

5 The object of the invention is to provide an improved construction which is simpler and cheaper than that now placed on the market.

According to this invention, net supporting and straining apparatus comprises a chain, to which the net supporting wire or rope is attached, adapted to engage around a sprocket wheel mounted at the upper extremity of the support, said sprocket being 15 rotated by a ratchet lever against the action of a pawl or pawls.

The support may consist of three metal tubes or bars of light section arranged in the form of a pyramid and rigidly attached to a 20 base plate.

In order that the invention may be understood, it will now be described with reference to the accompanying drawings in which Figure 1 is a perspective view of one form 25 of net supporting and straining apparatus constructed in accordance with this invention; Figure 2 is a fragmentary perspective view of the straining apparatus, and Figure 3 is an end view, drawn to a larger scale, of 30 the straining apparatus.

The supporting apparatus for the net *a* comprises two posts *b* and *c*. Each post consists of three metal tubes *d*, *d*, *d*, arranged in the form of a pyramid and rigidly attached 35 at their lower ends to a base plate *e* and their upper ends being connected by means of a bracket 2. Said base plate *e* is fitted, on its underside, with a hook *f* which is adapted to enter a hole *g* formed in the top of an 40 anchor plate *h* which is adapted to be driven into the ground and below the level of the surface thereof.

At the top of the post *b* is fitted a stud *j* on to which the standing end of the net rope 45 or wire is hooked. At the top of the post *c* is fitted the straining device which consists of a sprocket wheel *k* rotatably mounted on a shaft *l* in two of the tubes *d*.

The said sprocket wheel *k* is adapted to 50 receive a chain *m* which is secured to the other end of the net wire or rope.

Said sprocket wheel *k* is rotated by means of a hand lever *n* loosely mounted on the

shaft *l*, a projection *o* on said lever engaging a series of depressions or slots *p* in the side 55 of the sprocket wheel.

q, *q* are two pawls to prevent rotation of the sprocket wheel *k* in the reverse direction, the points *r* engaging in the slots *p*. The slots *p* on each side of the sprocket wheel 60 *k* and also the pawls *q* are staggered so that minute rotary adjustments of the wheel *k* can be effected. The said pawls are pivoted together at *s* and are so shaped that the points thereof always tend to engage the 65 said slots. *t*, *t*, are pivots about which the said pawls rock.

A squared boss *u* may be formed on the side of the sprocket wheel *k* in order that the said wheel may be rotated by means of a 70 separate spanner or the like, and in this case the lever *n* may be dispensed with.

With apparatus as above described, it is impossible for the straining wire to slacken owing to slip, and further, the said wire cannot become crippled by winding round a small drum. The posts being formed of tubes or bars of light section, can be carried much easier than those now in use. By sinking the anchor plate, there is no obstruction 75 so when mowing or rolling the lawn or court.

What I claim is:—

1. Apparatus for supporting and straining lawn tennis and like nets, comprising, a support, a base secured to said support, a hook on the underside of said base, a sprocket wheel rotatably mounted on said support, a chain adapted to engage said sprocket wheel, a hand lever to rotate said sprocket wheel, and two pawls pivoted to the support and adapted to engage with said 85 sprocket wheel.

2. Apparatus for supporting and straining lawn tennis and like nets, comprising, a support, a base secured to said support, a hook on the underside of said base, a sprocket wheel rotatably mounted on said support, a chain adapted to engage said sprocket wheel, a plurality of slots formed in each side of said sprocket wheel, a hand 95 lever loosely mounted on said support, a projection on said hand lever adapted to engage said slots, and two pawls pivoted to said support and adapted to engage said slots.

3. A lawn tennis net support comprising

a base plate, a vertical metallic rod secured to one end thereof, a pair of diagonally extending metallic rods secured to the opposite end of said plate, a bracket connecting the upper ends of said rods, the upper extremities of said diagonally extending rods projecting beyond said bracket and a sprocket

wheel of a net straining mechanism journaled within the projecting extremities of said diagonally extending rods. 10

In testimony whereof he affixes his signature.

EDMUND CLIFTON CARVER.
